CLAIM

The ornamental design for a smoke and carbon monoxide detector, as shown and described.

DESCRIPTION

FIG. 1 is a perspective view of a smoke and carbon monoxide detector, showing our new design;

FIG. 2 is a top view of the embodiment shown in FIG. 1; FIG. 3 is a bottom view of the embodiment shown in FIG. 1;

FIG. 4 is a side view of the embodiment shown in FIG. 1; FIG. 5 is another side view of the embodiment shown in FIG. 1;

FIG. 6 is a front view of the embodiment shown in FIG. 1; and,

FIG. 7 is a rear view of the embodiment shown in FIG. 1. The broken lines in the figures are included for the purpose of illustrating portions of the smoke and carbon monoxide detector and form no part of the claimed design.
